CLAIM

The ornamental design for a shoe, as shown and described.

DESCRIPTION

FIG. 1 is a bottom plan view of a shoe showing my design; FIG. 2 is a bottom rear perspective view thereof;

FIG. 3 is a bottom first side perspective view thereof; and, FIG. 4 is a bottom second side perspective view thereof.

The even-length broken lines are directed to environment, represent unclaimed subject matter, and form no part of the claimed design.

The long-and-short broken lines immediately adjacent shaded areas form an unclaimed boundary, and form no part of the claim.
